[57] **CLAIM**

The ornamental design for a holder for an artichoke or similar vegetable, as shown and described.

DESCRIPTION

FIG. 1 is perspective view of a holder for an artichoke or similar vegetable showing my new design;

FIG. 2 is a top plan view thereof;

FIGS. 3 and 4 are side elevational views thereof taken with respect to any of the points 45°, 135°, 225° or 315° in FIG. 2 (with 0° being at the top of this figure);

FIG. 5 is also a side, elevational view thereof taken with respect to any of the points 0°, 90°, 180° or 270° in FIG. 2 (with 0° being at the top of this figure);

FIG. 6 is a bottom plan view thereof.
